DIRECTIONAL ANTENNA SYSTEM

Kurt Koschmieder, Falkensee, Havelland, Germany, assignor to C. Lorenz Aktiengesellschaft, Berlin-Tempelhof, Germany, a company

Application July 17, 1937, Serial No. 154,153
In Germany July 18, 1936

1 Claim. (Cl. 250—11)

Directional antennae are known which are composed of individual antennae by which mainly the vertically polarized waves are received. In order to suppress the horizontal component, special precautions are necessary which reside in part in the constructional arrangement of the individual antennae themselves and in part in the provision of proper screenings. The antenna system best known in this regard is the so-called 10 Adcock antenna which consists of four vertical radiators erected in the angles of a square and interconnected crosswise. Such systems if carefully built up are faultless in operation. However it has been experienced that in certain cases 15 the desired result is not obtained. Investigations have shown this to occur if the electric earth is not homogeneous or not horizontal or fails to fulfill both these requirements.

A vertical antenna has a vertical characteristic 20 above the earth's surface if the electric constants of the ground are the same in all directions. Every discrepancy in this regard entails that a vertical antenna does not only transmit or receive vertically polarized waves but also transmits horizontally polarized waves or is excited by such waves. A vertical antenna erected on 25 not homogeneous ground is in electrical relation of the same properties as if it were standing aslant.

In order to compensate for the error arising 30 in this way the invention proposes so to incline the individual antennae in relation to the electric earth that horizontally polarized waves shall not be radiated or received, as the case may be. For 35 effecting the invention, preferably self-supporting antennae are employed which are so mounted at their lower ends that they can be positioned aslant. This arrangement has still other advantages over the customary antennae, as will be 40 understood from the following description, reference being had to the accompanying drawing in which.

Fig. 1 is a partially diagrammatic sectional elevation representing one embodiment of the 45 invention, Fig. 2 is a diagrammatic plan view of an antenna system composed of antennae of the construction shown in Fig. 1.

The antenna 1 is a self-supporting mast which at its lower end is mounted on an insulated platform 50 3 of a tripod 2. The antenna is held in position by clamps formed of insulators 4, 4 and 5, 5. Insulator 3 serves to sustain the weight of the

antenna 1. The insulators 4, 5 are arranged to hold the antenna against lateral displacement and are radially displaceable by means of screws 6, for instance, guided in suitable bushings 7 of the tripod 2, as shown in Fig. 1. Instead of this arrangement for displacing the insulators 5, 4 any other device may be employed. It will be seen that by displacing the insulators 4, 5 antenna 1 can be given positions different from the normal one, as shown in dotted lines. 10

The system represented in Fig. 2 is an Adcock antenna. In each of the four angles of a square an antenna 1 is erected which is of the construction illustrated in Fig. 1. In the middle of the system a transmitting or receiving apparatus 15 A is located. The means by which this apparatus and the antennae 1 are interconnected is in a purely diagrammatic manner represented by lines 8. In this system the individual antennae 1 are each given an oblique position which is such that 20 the horizontal polarization shall be suppressed in all directions.

The vertical antennae of the customary Adcock arrangements are a wire fixed at its upper end to a cantilever carried on a wooden pole. This arrangement too allows of effecting the invention, the pole and thus the cantilever having to be given an oblique position to such end. This arrangement however has the disadvantage that 25 with rainy weather the wet pole will have an influence upon the radiation characteristic. The novel arrangement has the advantage that field 30 distortions are avoided.

In addition, systems as provided by the invention are advantageous inasmuch as they are easy 35 to transport and to build up.

What is claimed is:

In a directional antenna system for receiving vertically polarized energy only, comprising an upright antenna mounted above the ground, 40 said ground having non-homogeneous conditions affecting the polarization of resultant received energy, the method of compensating for said non-homogeneous conditions to effect a substantial neutralization of the effects on the polarization, 45 comprising adjusting said antenna about a point at its lower end to a position inclined with respect to the ground at such an angle that the antenna will receive only vertically polarized waves, and maintaining said antenna in said adjusted position. 50
